UNITED STATES PATENT OFFICE.

OLE ANDRIAS THORSEN AND JOHN EDWARD SHUTT, OF GANADO, TEXAS.

FILLING-BOX FOR COTTON-PRESSES.

SPECIFICATION forming part of Letters Patent No. 634,839, dated October 10, 1899.

Application filed February 1, 1899. Serial No. 704,107. (No model.)

To all whom it may concern:

Be it known that we, OLE ANDRIAS THORSEN and JOHN EDWARD SHUTT, of Ganado, in the county of Jackson and State of Texas, have invented a new and Improved Filling-Box for Cotton-Presses, of which the following is a full, clear, and exact description.

Our invention relates to an improvement in boxes used in connection with cotton-presses for forming the bale preliminary to its insertion into the press proper.

Our invention comprises the novel features of construction, which will be hereinafter described and claimed.

Reference is to be had to the accompanying drawings, forming a part of this specification, in which similar characters of reference indicate corresponding parts in all the figures.

Figure 1 is a side elevation of our device, the flooring at the bottom of the box being shown in section. Fig. 2 is a plan view showing the supporting-shaft in section. Fig. 3 is a section taken through the pivot-bars upon which the sides of the boxes swing. Fig. 4 is a horizontal section of one of the hinges of the boxes, and Fig. 5 is a vertical section on the line 5 5 in Fig. 4.

Our device is one which has two boxes C arranged on opposite sides of a central pivot or standard A. The boxes are supported immediately above a circular section A' of the floor, which is carried by the central standard A and revolves therewith. The four sides of the boxes are constructed separable, so that the box may be opened for the insertion of the cotton. These boxes are alternately filled and then revolved beneath the press, where the cotton is compressed and discharged therefrom.

The boxes are mounted upon hinges of a peculiar construction. These hinges are pivoted upon vertical pivot-bars B', which are supported at their upper ends in a yoke B and at their lower ends in a similar yoke, or by means of pivot-plates B², which are secured to the floor A'. These pivot-bars are substantially in line with the sides of the boxes, and the adjacent ends of the boxes are removed some distance from the pivot-bars.

The pivot-bars B' have collars G' secured thereto and determining the vertical position of the hinges D, which lie between said col-

lars. These collars G' and the eyes of the hinges are provided with circular grooves which receive balls G, thus making the pivot 55 a ball-bearing one. The hinges are secured at their outer ends by means of flanges E' to the sides C' and C² of the boxes. As herein shown, these hinges are made adjustable in length, and the eyes are made in two parts, so 60 that they may be conveniently put in position and removed. The eyes are formed of two semicircular sections D' and D², which are provided at one end with ears, through which passes a securing-bolt d', and at their opposite ends are provided with extensions D³ and D⁴, which have a channel or recess in their inner or adjacent edges adapted to receive an extension member E, by which the length of the hinge may be adjusted. A bolt d, passing 65 through this portion of the hinge, secures the various parts together.

One of the bars which forms the eye is provided within the recess which is formed in its extension D³ with teeth, which are adapted 75 to be engaged by corresponding teeth upon the extension member E, so that the parts may be firmly held in adjusted position. By this means the hinges may be adjusted through a considerable range, and thus enable the same hinges to be used for presses in which the location of the boxes somewhat varies.

The bar D², which forms one portion of the hinge, is provided with ears F², to which is 85 pivoted a link F, which at its other end is pivoted to a plate F', secured to the end section C² of the box. The end section C² of the box is similarly pivoted to a link F upon its opposite edge, being thus supported at each 90 edge and at top and bottom. The point of connection of the link F to the hinge is between the pivot-point of the hinge and its end, and the link swings in an arc of a circle as the side C' or C² opens. As a result of 95 this construction and when a side C² or C' is swung open the end section C² will be moved toward the central standard A in the manner shown by the dotted lines in Fig. 2. This moves both end and side sections simultaneously away from the cotton which is within the box. The other end section C⁴ is pivoted at H upon one of the side sections, the one to which it is pivoted being determined by 100

whether the press is a right or left handed one. The free end of the section C¹ is secured to the opposite side section by means of a latch H¹ of any suitable construction. 5 The upper end of the central standard A is supported by means of a beam A², which extends over the boxes.

By providing the hinges with ball-bearings in the manner described the sides are swung 10 with little exertion, and the boxes may be firmly supported without using rollers or a track for the same. To more rigidly support the boxes, stay-rods or braces I are employed, which extend from eyes I¹ in the upper set of hinges and located as near their pivot-point as possible to similar eyes I², located upon the under set of hinges and as far from their pivots as possible. This supports the boxes more rigidly.

20 Having thus fully described our invention, we claim as new and desire to secure by Letters Patent—

1. A filling-chamber for cotton-presses, having its sides and ends separable, the sides being mounted on arms at one end, pivots for the outer ends of said arms, and links connecting said arms near their pivots with the adjacent end section of the chamber, whereby the end section is moved outwardly by the 30 swinging outward of the sides, substantially as described.

2. In filling-boxes for cotton-presses, the combination of a central supporting-standard, a yoke supported thereon, pivot-bars carried by the yoke ends, hinges upon said pivot-bars, a box having its sides carried by the 35 hinges, the box end next the central pivot being separable from its sides, and links pivoted to the body of the hinges and to the said 40 box end, substantially as described.

3. In filling-boxes for cotton-presses, the combination of a central supporting-standard, a yoke supported thereon, pivot-bars carried by the yoke ends, hinges upon said pivot-

bars, a box having its sides carried by the 45 hinges, the box end next the central pivot being separable from its sides, and links pivoted to the body of the hinges and to the said box end, the opposite box end being hinged to one of the sides, and means for securing 50 the outer edge of this end to the other side, substantially as described.

4. In filling-boxes for cotton-presses, the combination of a central standard, vertical pivot-bars, top and bottom supports therefor 55 extending from the central standard, the pivot-bars being approximately in line with the sides of the boxes, boxes formed of separable side and end sections and located on opposite sides of the central standard, hinges 60 journaled upon the pivot-bars and secured to the adjacent ends of the side sections of the boxes, and links pivoted to the body of the hinges and to the adjacent end section of the boxes, the outer end sections of the boxes 65 being pivoted to one of the side sections, and catches for securing the swinging edges of the said outer end sections to the other side sections, substantially as described.

5. In filling-boxes for cotton-presses, the 70 combination of a central standard, vertical pivot-bars approximately in line with the sides of the boxes, supports for said pivot-bars extending from the central standard, a box formed of separate side and end sections 75 and located at one side of the central standard and pivot-bars, top and bottom hinges journaled upon the pivot-bars, and stays extending from the inner end of the upper hinge to the outer end of the lower hinge, the filling-box being secured to said hinges, substantially as described.

OLE ANDRIAS THORSEN.
JOHN EDWARD SHUTT.
